DAVID W. SILVERS, OF LOS ANGELES, CALIFORNIA

DESIGN FOR A LIGHTING-FIXTURE GLOBE

Application filed July 9, 1929. Serial No. 31,978. Term of patent 3½ years.

To all whom it may concern:

Be it known that I, DAVID W. SILVERS, a citizen of the United States of America, and a resident of Los Angeles, county of Los Angeles, and State of California, have invented a new, original, and ornamental Design for a Lighting-Fixture Globe, of which the following is a specification, reference being had to the accompanying drawing, forming a part thereof.

In the drawing:

Figure 1 is a perspective view of the lighting fixture globe,

Figure 2 is an inverted plan view of the same, and Figure 3 is a sectional view on line 3—3 of Figure 2.

I claim:

The ornamental design for a lighting fixture globe substantially as shown.

DAVID W. SILVERS.
